UNITED STATES PATENT OFFICE

2,094,393

PRECAST CONCRETE BUILDING CONSTRUCTION

Abraham J. Blackstone, Chicago, Ill.

Application February 12, 1937, Serial No. 125,474

7 Claims.

(Cl. 72—1)

An object of this invention is to provide an improved building construction having a steel framework which is fabricated in the shop and wherein the exterior sections of the building are 5 pre-cast concrete, all for quick and easy assembly on the ground by unskilled labor.

Another object is to provide a ready means for securing metal lath to the steel framework.

These and other objects, as will hereinafter appear, are accomplished by this invention which is fully described in the following specification and shown in the accompanying drawings, in which—

Figure 1 is a partial perspective of a one-story house embodying the invention;

15 Figs. 2, 3, and 4 are enlarged partial sections on the lines 2—2, 3—3, and 4—4, respectively, of Fig. 1; and

20 Figs. 5, 6, and 7 are enlarged elevations of concrete building sections as viewed from the reverse side.

The embodiment illustrated comprises a building having a steel framework with corner columns A, intermediate outside columns as B, resting upon suitable fittings or foundations (not shown) 25 and connected by horizontal beams C, D, E, F, etc., which are connected to the columns in any well known manner as by means of connecting angles (not shown) which are riveted or bolted for rigid but quick assembly of the building in the field.

The exterior of the building is made up of a series of pre-cast concrete sections as 10, 11, 12 which are suitably supported by the beams. Thus the section 10 is made up of concrete or the 35 like suitably reinforced with metal, and has an inwardly projecting rib 10^a serving as a ledge adapted to rest on the top flange of the beam C. This section overlaps the columns A and B, and is provided with a number of studs or bolts 10^b, 10^c, etc. (Fig. 7) at suitable intervals which are preferably cast in vertical ribs 10^d in the section and at the lower end are adapted to pass through the upper flange of the beam C so as to maintain this section on the beam.

45 The section 10 also has an upper horizontal rib 10^e with which the vertical ribs connect. A bolt 14 is cast into each end of the horizontal rib 10^e near its end, as shown in Figs. 3 and 7, and passes through holes in the end of a metal strap 15 which lies across the two flanges of the column B. These bolts have nuts by means of which the sections may be drawn up tightly against the column. The ends of adjacent sections, however, do not 50 meet, and the space therebetween is filled as will later be described.

The intermediate concrete section 11 may have a window, as 16, or window frame cast therein preferably of metal. This section preferably has 55 top and bottom horizontal ribs 17, 18, respectively,

cast integral as well as connecting vertical ribs 19, 20.

The rods 10^b, 10^c (Fig. 7) serve several purposes. These rods extend through the vertical ribs 10^d acting as reenforcing rods; the lower ends of the rods 5 serve to position the section on the supporting beam C while the upper ends of these rods are preferably threaded to receive a screw threaded eyelet or the like, not shown, which is used when the concrete section is being moved both during the manufacturing operation and during 10 erection in the building. After erection the eyelet is unscrewed, leaving the upper ends of the rods protruding from the sections. Metal tubes 21 are cast into the lower rib and positioned to surround 15 the upper end of each of these rods when the intermediate section 11 is inserted in place, as shown in Fig. 4. The upper ends of the section 10 and both the upper and lower ends of the section 11 are secured to the vertical column by 20 means of bolts 14^a which are similar to bolts 14 and are cast in these sections in the same way. The upper end of the section 11 is provided with bolts 22, 23 which extend beyond the upper surface of the section and serve the same purposes 25 as the upper ends of the rods 10^b, 10^c.

In a one-story building the upper portion may be finished by means of sections as 12, each of which has a lower rib 24 which has bolts 14^b (similar to the bolts 14, 14^a) cast therein at each end 30 for securing this section to a column, as the column A, by means of a metal plate 25. The lower rib 24 is provided with metal pipes 26, 27 which are adapted to register with the bolts 22, 23 so as to position one section with respect to the other. 35

The upper section 12 is provided with a ledge 12^a which rests upon the beam E (Fig. 4) and has two or more rods 28 cast therein and extending down so as to pass through registering openings in the flange of the beam E to position this section with respect to the beam. 40

The vertical space in front of the column B (Fig. 3) is now filled by means of a vertical corner filler strip 29 which has suitable metal reinforcing 45 29^a and has a series of bolts 30 cast therein and passing through suitable registering openings in the web of the column A having nuts 31 by means of which the filler strip can be drawn up tightly against the column. This filler strip overlaps the ends of the sections 12, 12. A suitable cement or mortar 32 serves to fill the space 50 between the filler strip and the column.

Similarly a vertical filler strip 33 is secured to each of the intermediate columns B along the 55 side wall and is secured thereto by means of bolts 34. In this form the center portion 33^a of the filler strip is preferably raised so as to extend between the ends of the sections 10, 10, and 11, 11, and 12, 12, while as before the space 35 between 60

the filler strip and the column is filled with a suitable mortar.

Thus it will be seen that a very simple and efficient means is provided for constructing and erecting the frame work and side walls of a building. While the building shown is only a one-story building, it will be understood that it may readily be carried up two, three or more stories, as desired. The sections as described are pre-10 cast and are brought on the lot where the building is to be erected. Erection can now be accomplished by means of unskilled labor and in a very short time.

The method of inserting floors, side walls and 15 the roof will now be described. A concrete floor slab 36 rests on cross beams as D and is preferably pre-cast with suitable reinforcing rods (not shown) in a well known manner. If desired, a sub-floor 37 of one inch boards or the like may 20 be laid on the lower flange of the beams C and D. Rock wool 38 may be placed thereon to serve as a heat insulator. The space between the top of the rock wool and the bottom of the floor slab 36 serves as a dead air space which also acts 25 as a heat insulator.

The roof may be made up of a series of pre-cast concrete roof slabs 39 supported on the steel beams F. A flashing 40 of copper or the like is brought down over the roof slab 39, and a 30 suitable covering 41 of asphalt or the like is applied thereto so as to render the whole water-proof.

A screen as of chicken wire 42 is stretched over the ribs as assembled and nailed to the ribs, and 35 a cork board or strip 43, or the like, is placed over each rib to act as a heat insulator to prevent condensation of moisture on the inner walls opposite the ribs.

To support the plaster, I may use horizontal 40 channels 44 (Fig. 2) which are secured to the columns by means of wires 45 passing through a hole in the column and vertical channels and studding 46 are secured to the horizontal channels by means of wires 47. The studding have straight 45 wires 48 passing therethrough. Over these a wire lath 49 or the like, preferably having a paper backing, is placed with the ends of the wires protruding therethrough. These ends are then bent over as shown to retain the lath on the studding. 50 Plaster 50 is put on the lath in the usual way.

The space between the wire screen 42 and outside surface of concrete wall section is then filled with rock wool or the like 51, while the space 52 between the screen 42 and the vertical concrete 55 sections acts as a dead air space.

In Fig. 4 is shown another method of interior finishing in which rock lath 53 is carried some distance in front of the cork strips 43 as by means of wood strips or studding (not shown) so 60 as to leave a space to be filled with rock wool 51a.

Thus it will be seen a very efficient but inexpensive means of insulating the walls, floors, and roof against heat and cold is attained and one which provides a very satisfactory wall finish.

65 I claim:

1. In a building construction, a steel framework comprising columns and beams secured together, wall beams lying adjacent the outer walls, pre-cast wall sections adapted to lie outside said 70 wall beams and having means for supporting the wall sections on the wall beams, certain of the

wall sections each having a main slab lying outside the plane of the beams and having inwardly extending spaced horizontal ribs certain of which have ledges adapted to rest on the beams, and vertical ribs connecting the horizontal ribs and spaced inwardly from the ends. 5

2. In a building construction, a steel framework comprising columns and beams secured together, wall beams lying adjacent the outer walls, pre-cast wall sections adapted to lie outside said wall beams and having means for supporting the wall sections on the wall beams, certain of the wall sections each having a main slab lying outside the plane of the beams and having inwardly extending spaced horizontal ribs certain of 10 which have ledges adapted to rest on the beams, vertical ribs connecting the horizontal ribs and spaced inwardly from the ends, and rods at the upper and lower ends of said vertical ribs of a section for positioning said section with respect 20 to the building members above and below it.

3. In a building construction, a steel framework comprising wall columns and beams secured together, wall beams lying adjacent the outer walls, pre-cast concrete wall sections having edge 25 portions overlapping the wall columns, and means for securing these overlapping sections to the columns including a vertical filler strip overlapping the edge portions.

4. In a building construction, a steel framework comprising wall columns and beams secured together, wall beams lying adjacent the outer walls, pre-cast concrete wall sections having edge 30 portions overlapping the wall columns, and means for securing these overlapping sections to the 35 columns including a vertical filler strip overlapping the edge portions, said filler strip having bolts extending through the columns.

5. In a building construction, a steel framework comprising wall columns and upper and 40 lower beams secured to the columns, a lower pre-cast wall section having a slab lying outside the columns and beams with an inwardly extending rib resting on the lower beam, a similar upper 45 wall section resting on the upper beam, and an intermediate wall section resting on the lower section and guided by the upper section.

6. In a building construction, a steel framework comprising wall columns and upper and lower beams secured to the columns, a lower pre-cast wall section having a slab lying outside the columns and beams with an inwardly extending rib resting on the lower beam, a similar upper wall section resting on the upper beam, and an intermediate wall section resting on the lower section 55 and guided by the upper section, each section having a lip overhanging the section beneath.

7. In a building construction, a steel framework comprising wall columns and upper and lower beams secured to the columns, a lower pre-cast wall section having a slab lying outside the columns and beams with an inwardly extending rib resting on the lower beam, a similar upper wall section resting on the upper beam, an intermediate wall section resting on the lower section 60 and guided by the upper section, sections at the same level on opposite sides of the columns having studs extending inwardly adjacent the column, and means yieldingly connecting the studs and column. 65

ABRAHAM J. BLACKSTONE.
